SIGN LIGHT LENS

Franklin M. Neal, Corning, N. Y., assignor to Corning Glass Works, Corning, N. Y., a corporation of New York

Application April 29, 1954, Serial No. 30,247

Term of patent 14 years

(Cl. D48—32)

Fig. 1 is a front elevational view of a sign light lens embodying my new design.

Fig. 2 is a side elevational view thereof.

Fig. 3 is a sectional view taken on line 3—3 of Fig. 1.

I claim:

The ornamental design for a sign light lens, as shown.
